UNITED STATES PATENT OFFICE.

WILLIAM E. MAYHEW, OF STOCKTON, CALIFORNIA.

LOADER.

1,412,952.

Specification of Letters Patent. Patented Apr. 18, 1922.

Application filed September 14, 1920. Serial No. 410,187.

To all whom it may concern:

Be it known that I, WILLIAM E. MAYHEW, a citizen of the United States, residing at Stockton, county of San Joaquin, State of California, have invented certain new and useful Improvements in Loaders; and I do declare the following to be a full, clear, and exact description of the same, reference being had to the accompanying drawings, and 10 to the characters of reference marked thereon, which form a part of this application.

This invention relates to improvements in loading devices, being particularly adapted and intended to be used for the purpose of 15 loading hay into wagons, as said loader and wagon move together across a field over which the shocks of hay are scattered at more or less regular intervals.

The principal object of the invention is 20 to provide a device of this character by means of which the hay etc. may be raised from the ground and deposited in a wagon alongside, without halting the progress of either the loader or wagon, and which requires only the services of a single operator 25 to manipulate the device.

Another object is to provide a device which will work equally well on a side hill or on a grade of any kind.

30 I have also arranged the working parts of the device so that they may be operated by engine power, or by power derived from the rotation of the supporting wheels of the loader as it moves along.

35 The loader can also be operated while stationary, by means of a draft horse or otherwise.

I particularly believe to be novel the use 40 of a stationary track projecting beyond one side of the device, in connection with the carrier and the loading fork suspended from the track. This feature does away with the use of a swinging boom as ordinarily employed, and enables the loading operations 45 to be considerably accelerated.

These objects I accomplish by means of such structure and relative arrangement of parts as will fully appear by a perusal of the following specification and claims.

50 In the drawings similar characters of ref-

erence indicate corresponding parts on the several views.

Fig. 1 is a side elevation of the loader.

Fig. 2 is a top plan view of the same.

Fig. 3 is a front end view thereof.

Fig. 4 is a perspective view of the grab or fork.

Fig. 5 is a fragmentary section taken on a line 5—5 of Fig. 4, showing a catch member. Fig. 6 is an enlarged view of the carriage trip or stop.

Referring now more particularly to the characters of reference on the drawings, the numeral 1 denotes a suitably formed horizontal frame supported at its forward end 65 by wheels 2, and at its rear end by a tiller wheel 3.

At the forward end of the frame and mounted between the wheels for limited vertical movement in guides 4 on the frame, is 70 a vertical frame 5 having horizontal prongs 6 projecting forward, the outer prongs having brace bars 7 extending up to the frame at an angle to the wheels, this frame and prongs being a rigid unit and forming a 75 shoe or support for the reception of the fork or grab 8 which comprises a normally vertical frame 9, having long prongs or teeth 10 projecting forward from the lower side thereof and shorter prongs 11 projecting 80 forward from the sides. Rigid bars 12 at right angles to the frame 9 and fixed thereto, project convergently forward a certain distance, their outer ends being connected by a piece 13 containing a spring pressed 85 catch 14 of any ordinary type, which is adapted to normally engage a transverse bar 15 fixed on the outer ends of a pair of arms 16 pivoted to the upper ends of the frame 9, the bar and arms together forming a yoke. 90 Projecting up from the frame 1, being pivoted thereto as at 17 and being in vertical alignment with the shoe-frame 5 are beams 18, connected together at suitable intervals by light and flexible transverse bars 95 19, to which are fixed vertical guide or rest bars 20 against which the fork-frame bears when raised.

Pivots mounted to the beams 18 at the top thereof and extending lengthwise of the 100

frame 1 and in parallel relation are beams 21, projecting over the fork 8, there being a spaced and connected pair of such beams to each of the beams 18.

5 Slidably mounted to and between each pair of beams 21 forward of the beams 18 are blocks 22 arranged to be positioned and held at predetermined points. These blocks support a transverse track 23 hung thereunder by means of flexible link connections 24, this track extending beyond the wheel 2 on one side for a considerable distance so that it will overhang a wagon which may be alongside the device.

10 15 Riding on this track is a carrier 25 of any of the standard forms, having the usual trip or stop 26 mounted in connection with the track at a point directly above the fork 8 when seated in the shoe.

20 25 To operate the fork and carrier, a pulley block 27 is fixed to the bar 15, around which a cable 28 passes from a fixed end on the carrier, then around a sheave 29 on the carrier and around a sheave 30 on the outer end of the track. From there the cable passes over sheaves 31 mounted in the blocks 22 and is led thence over other suitably positioned sheaves 32 to a drum 33 mounted on the frame 1.

30 35 In operation, a pull on the cable raises the fork to a point adjacent the carrier, and a further pull on the cable throws the trip and causes the carrier and fork to move along the track toward the outer end thereof, so that the fork with its load is above the wagon positioned alongside the loader.

40 45 The load is then dumped by releasing the trip or catch 14, which is done by means of a rope 34 which leads over a sheave 35 mounted on the adjacent block 22 to a point convenient to the operator, who has his stand on a platform 36 on the frame 1 near the tiller wheel. To return the fork to its loading position in the shoe, a rope 37 is provided which extends from a winch 38 over suitable sheaves 39 to the pulley block 27.

50 55 Thus by pulling on the rope 37 when the carrier and fork are in their upper and outermost position, and at the same time allowing the drum 33 to turn to pay out the cable 28, the carrier is brought above the shoe, the trip again engages, and the fork may then be lowered to its seat in the shoe.

60 65 To guide said fork into position so that it will not foul with the frame 1, the guide bars 20 are provided, as previously described, while the outer ends of the bars 19 are rounded as at 19^a so that when the fork, which is very possibly swinging, is moved transversely, it will be engaged and moved into position without catching.

To hold the arm 15 from swinging around when the fork is moved beyond the plane 65 of the bars 20, auxiliary guide bars 41 pro-

ject downward from the carrier 25 and engage said arm, these bars alining with the bars 20 when the carrier moves to its central or innermost position.

To allow for fore-and-aft movement of the vertical beams 18 and to brace and hold them rigid in any set position, I provide brace-beams 42 pivotally mounted to the beams 18 about half way up, and which extend rearwardly to upwardly projecting extensions 43 on the frame 1, to which extensions said beams are adjustably mounted.

70 75 Brace links 44 extend from the beams 42 a certain distance below their pivotal connections to the rear end of the beams 21, said links being pivoted at both ends.

80 Thus by altering the point of connection of the beams 42 with the member 43, the setting of the beams 18 and 21 is altered accordingly, the front ends of the latter 85 sloping either downwardly or upwardly as may be desired, while at the same time the flexible mounting of the track permits it to always hang in a vertical plane.

85 90 Since the beams 18 and 21 and 42 are practically independent units, the setting of the one may be altered without disturbing the setting of the other, so that no matter what the angle of setting of the loader as a whole may be relative to a true horizontal plane, the track 23 may be maintained in true horizontal alinement.

95 100 The adjustable features just described therefore permit the device to be efficiently used in side-hill work and on longitudinal gradients as well.

105 110 When the fork is lowered into position into the shoe, the bar 15 and arms 45 naturally hang vertically, the catch holding them to the frame 12 having been released when the fork was dumped. To reposition this bar 15 so that the catch 14 will be engaged prior to a lifting movement of the cable 28, I provide a pair of arms 45 pivoted to the frame 1 behind the fork and normally projecting upward sufficiently to engage the bar 15. Another arm 46 is mounted in connection with the arms 45 and has a cable 47 attached thereto and extending to a free end adjacent the operator, this cable and arm being arranged to throw the arms 45 and consequently the bar 15, downward and forward, so that the catch 14 engages the bar 15, when the cable 47 is pulled.

115 120 To rotate the cable drum 33, I preferably provide an engine 48 mounted on the frame 1 and operatively connected with said drum, there being a clutch 49 interposed therebetween so that the engine may be disconnected from said drum at will.

125 If an engine is not desired, power to rotate the drum may be taken from one of the wheels 2 by means of a chain drive as indicated at 50, which drive would of course have a suitable clutch interposed to break

the driving connection at will. Or an auxiliary drum 51 may be provided, which would be operatively connected with the drum 33, the cable on this drum 51 being unwound by being pulled by a draft animal attached at its outer end, while the cable 28 is being wound on the drum 33.

5 The winch 38 may also be connected to be driven by the engine if desired, though I have shown it as being hand-turned.

10 In the operation of the device, the loader is moved forward either by a tractor or by draft animals, positioned at the rear. The device is steered while moving so that a 15 shock of hay is forced into the fork. When the latter is loaded, the arms 45 are manipulated to cause the bar 15 to lock with the fork-frame 13, and the cable 28 is then wound on the drum 33, raising the fork up 20 and finally over beyond the loader, the point of pull on the fork being positioned so that the latter is held with its open side substantially facing upward.

25 When the catch 14 is released however, the weight of the load causes the fork to tip, and the load is instantly dumped. The operations then necessary to return the fork to its loading position have been already described.

30 When it is desired to transport the loader from place to place without operating the same, the shoe is raised clear of the ground by means of a lever 52 pivoted to the frame 1 and extending from the rear of the shoe 35 to a point adjacent the operator.

35 From the foregoing description it will be readily seen that I have produced such a device as substantially fulfills the objects of the invention as set forth herein.

40 While this specification sets forth in detail the present and preferred construction of the device, still in practice such deviations from such detail may be resorted to as do not form a departure from the spirit of the 45 invention, as defined by the appended claims.

45 Having thus described my invention, what I claim as new and useful and desire to secure by Letters Patent is:—

1. A loader comprising a wheel-mounted 50 frame, a pronged shoe mounted at the forward end of the frame and resting adjacent the ground, a fork adapted to rest in the shoe to be loaded, and means for then raising and moving the fork to one side to 55 dump the same.

2. In a loading device, a loading fork adapted to be raised from the ground, such fork comprising a frame structure open on its forward side when on the ground, a yoke 60 pivoted at the upper rear ends of said structure, the outer end of the yoke being connected to a raising means, a releasable catch in the frame structure adapted to automatically engage and hold the yoke when the latter

is moved to a horizontal position, and means 65 on the loader and actuated therefrom for moving said yoke to a position to be engaged by the catch.

3. A loader comprising a wheel supported frame, vertical beams at the front end of the frame, a transverse track extending beyond one side of the frame and supported from the beams, said track having a carrier mounted thereon, and means for adjusting the beams to maintain the horizontal position of the track irrespective of the setting of the loader.

4. A loader comprising a wheel supported frame, vertical beams at the front end of the frame, longitudinal and horizontal beams 80 pivotally mounted at the upper ends of the vertical beams and extending forward therebeyond, a transverse track flexibly suspended from the longitudinal beams, and independent means for each such beam for altering 85 the horizontal alignment thereof, whereby the horizontal transverse alignment of the track is altered.

5. A loader comprising a wheel supported frame, vertical beams at the front end of the frame, longitudinal and horizontal beams pivotally mounted at the upper end of the vertical beams and extending forward therebeyond, a transverse track flexibly suspended from the longitudinal beams, brace beams 95 pivotally mounted to the vertical beams and adjustably secured to the frame and links pivotally connected to the brace beams and to the longitudinal beams.

6. A loader comprising a wheel supported frame, a pronged shoe at the forward end positioned adjacent the ground, a vertical framework projecting upwardly from the frame at the rear of the shoe, a transverse track supported by the vertical frame and 105 extending therebeyond on one side, a carrier on the track, a loading fork connected to the carrier and adapted to rest in the shoe when being loaded, and a common means for raising the fork to a point adjacent the carrier 110 and for then moving the carrier and fork to the outer end of the track.

7. In a loading device, a loading fork adapted to be raised from the ground, such fork comprising a frame structure open at 115 its forward side when on the ground, a yoke pivoted at the upper rear ends of said structure, the outer end of the yoke being connected to a raising means, a releasable catch in the frame structure adapted to automatically engage and hold the yoke when the latter is moved to a horizontal position and a pair of arms pivoted in common and positioned in the vertical plane of the arms of the yoke and behind the same, and adapted 125 to be moved to bear against and move the yoke into the path of the catch when the fork is on the ground.

8. In a loading device, a loading fork having a normally vertical frame portion, a vertical framework on the loader behind the fork, a transverse track mounted on top of the framework and projecting therebeyond, a carriage movable along the track and to which the fork is connected, means for rais-

ing the fork and then moving the carriage to one side, vertical guides on the framework against which the fork-frame bears when being raised, and vertical guides projecting downwardly from the carriage. 10

In testimony whereof I affix my signature.

WILLIAM E. MAYHEW.
